UNITED STATES PATENT OFFICE.

LOUISA WOHLTMAN, OF NEW YORK, N. Y.

DESIGN FOR A SOUVENIR-PLATE.

SPECIFICATION forming part of Design No. 36,013, dated August 19, 1902.

Application filed June 26, 1902. Serial No. 113,306. Term of patent 14 years.

To all whom it may concern:

Be it known that I, LOUISA WOHLTMAN, a citizen of the United States, residing in the borough of Manhattan, city of New York, county of New York, and State of New York, have invented and produced a new, original, and ornamental Design for a Souvenir-Plate, of which the following is a specification, reference being had to the accompanying drawing, forming part thereof.

This invention relates to ornamental designs for souvenir-plates.

The accompanying drawing shows a front view of my new design.

As shown in the drawing, the leading or material feature of my design consists in a center disk A, having a raised circumferential rim B. About the center disk A are arranged eight horseshoes C and eight anchors D, the said horseshoes C and anchors D alternating around the said disk A, the lower part or heels E of the said horseshoes C and the top part or eye F of the said anchors D resting on the rim B. At the top of each of said horseshoes C is a raised toe G, and at the bottom of said horseshoes C are raised heels E. On each side of the said horseshoes C is a groove H, extending from the toe G down each side of said horseshoes C, and in each of said grooves H are three depressions I to represent the holes for the nails of the said horseshoes C, and on each of said horseshoes C are raised beads J. At the end of the lower part or flukes of said anchors D are raised points K, and on the cross-bar L are four bands M. The raised points K and the cross-bar L of the anchors D rest upon the horseshoes C.

Having described my invention, what I claim as new, and desire to secure by Letters Patent, is—

The ornamental design for a souvenir-plate as herein shown and described.

In testimony whereof I have signed my name to this specification in the presence of two subscribing witnesses.

LOUISA WOHLTMAN.
